UNITED STATES PATENT OFFICE.

MARY V. GRIFFITH, OF BALTIMORE, MARYLAND.

FURNITURE.

1,173,954.

Specification of Letters Patent. Patented Feb. 29, 1916.

Application filed June 23, 1915. Serial No. 35,854.

To all whom it may concern:

Be it known that I, MARY V. GRIFFITH, a citizen of the United States, residing at Baltimore, in the State of Maryland, have invented new and useful Improvements in Furniture, of which the following is a specification.

This present invention relates to improvements in furniture.

10 In carrying out my present invention it is my purpose to construct an article of furniture in the nature or form of a chair to provide the same with auxiliary members so arranged upon and associated with the chair as 15 not to detract from the appearance of the chair but, as a matter of fact, to reinforce the said chair, the said auxiliary members being further adapted, when moved or 20 swung away from the chair, to convert the chair into a crib or lounge. I also propose to provide an article of furniture, such as an ordinary chair, with panel members adapted to hold against the side, back and over the 25 seat of the chair, and which, when swung away from the chair, will produce a separate article of furniture, such as a crib or lounge.

It is a further object of my invention to construct convertible furniture which shall be cheap, simple, strong and effective.

30 Further objects and advantages will appear as the nature of the invention is more fully understood, reference being had to the accompanying drawings in which there is illustrated a simple and satisfactory reduction of the improvement to practice, and in which—

Figure 1 is a perspective view of an article of furniture constructed in accordance with the present invention, the same being shown in the form of a chair; Fig. 2 is a similar view showing the chair converted into a lounge or crib; Fig. 3 is a central vertical longitudinal sectional view of the device illustrated in Fig. 1; Fig. 4 is a rear elevation of the same; Fig. 5 is a central vertical longitudinal sectional view through the device illustrated in Fig. 2; and Fig. 6 is a detail perspective view of the end of one of the auxiliary side members.

50 In the drawings 1 designates a chair, which may be of the ordinary construction, or which may be of a special design should the same be found desirable in carrying out my invention.

55 The chair preferably has its back 2 extended a suitable distance above its side

arms 3, and the said arms preferably project outwardly from the sides of the chair. The seat 4, at the outer end thereof, has hinged thereto, as at 5, an auxiliary seat 6 which, as shown in Figs. 1 and 3 of the drawings, is adapted to be swung over the seat 4, and the face of the auxiliary seat 6, providing the upper face thereof when in such position, may be upholstered if desired. The inner 65 edge of the auxiliary seat has its opposite corners provided with hinges 7 to which are secured lugs 8 that are adapted to support the auxiliary seat 6 when the seat is swung to the position illustrated in Figs. 2 and 5. 70 Hingedly secured to the front stiles of the chair 1, as at 9—9, are panel members or auxiliary sides 10—10, the said auxiliary sides of the chair 1, as shown in Fig. 1 of the drawings, being adapted to be received beneath the ledges of the arms 3 of the said chair 1 and their hinges are so arranged that when the said members 10 are swung outwardly of the chair 1 as shown in Figs. 2 and 5 the opposite faces of the members 10 75 will be disposed flush with the opposite faces of the sides proper of the chair 1. Hingedly connected, as at 11—11, to one of the edges of one of the auxiliary sides or panels 10, is a similar panel 12, the same including top 80 and bottom plates 12'—12' which project a suitable distance beyond the panel proper of the member 12 and which are provided and adjacent the said projecting portions with spaced openings 13—13. The free end 85 of the side panels opposite that provided with the panel 12 have their end stiles provided with longitudinally extended threaded studs 14—14, and these studs are adapted to be received within the outer openings 13 90 of the members 12' of the panel 12 when the said panel 12 is swung against the back 2 of the chair 1 when the device is in the position illustrated in Figs. 1, 2 and 3, the said studs 14 being received within the other 95 opening of each of the members 12' when the panel 12 is swung to provide the end or gate member for the crib, as illustrated in Figs. 2 and 5.

The numerals 15 designate thumb nuts 105 which engage with the threaded studs 14 to sustain the panel 12 when the same is arranged against the back of the chair 1, or when the same is arranged as an end or closure member for the crib or lounge.

110 From the above description, taken in connection with the drawing, the simplicity of

my device, as well as the advantages thereof, will, it is thought, be apparent to those skilled in the art to which said invention appertains without further detail description.

5 Having thus described my invention, I claim:

1. An article of furniture, a chair, auxiliary side panels hingedly secured to the front stiles of the chair, a panel secured to 10 one of the auxiliary side members, means for securing the said panel to the other auxiliary side member, an auxiliary seat hingedly secured to the outer end of the seat of the chair, and hinged legs upon the said 15 auxiliary seat.

2. A convertible article of furniture, as herein described, including a chair, an auxiliary seat hingedly secured to the seat of the chair, hinged legs for the said auxiliary 20 seat, means for sustaining the legs at right

angles to the said seat when the same is swung on a line outward from the seat of the chair, the sides of the chair having arms which project laterally therefrom, auxiliary side members hinged to the front stiles of the chair and disposed beneath the arms, a panel member hingedly secured to the free end of one of the auxiliary sides, the other auxiliary side having projecting threaded studs which pass through openings in the last mentioned panel, a removable element 30 engaging the said studs for retaining the panel upon the said last mentioned auxiliary side.

In testimony whereof I affix my signature 35 in presence of two witnesses.

MRS. MARY V. GRIFFITH.

Witnesses:

ANDREW C. LAWRENCE,

LOUISE C. WEISBROD.
